TOILET PAPER HOLDER

Filed July 6, 1931

Fig. 2

INVENTOR:—

JOSEPH H. ALLEN.
BY *Martin D. Smith, Atty*

UNITED STATES PATENT OFFICE

JOSEPH H. ALLEN, OF ALHAMBRA, CALIFORNIA

TOILET PAPER HOLDER

Application filed July 6, 1931. Serial No. 548,730.

My invention relates to a toilet paper holder and has for its principal object, the provision of a relatively simple, practical and inexpensive bracket for conveniently holding a roll of toilet paper and to construct the bracket so that the roll of toilet paper may be very easily and quickly applied to the holder.

A further object of my invention is, to 10 provide a holder of the character referred to that will receive and conveniently hold a roll of toilet paper without the requirement of a spindle of wood or metal and which latter is an essential part of the roll 15 toilet paper holders now in general use.

With the foregoing and other objects in view, my invention consists in certain novel features of construction and arrangement of parts that will hereinafter be more fully 20 described and claimed and illustrated in the accompanying drawing in which:

Fig. 1 is a perspective view of a toilet paper holder constructed in accordance with my invention and showing a roll of paper 25 supported thereby.

Fig. 2 is a vertical longitudinal section taken on the line 2—2 of Fig. 1.

Fig. 3 is a top plan view of one of the hinged fingers that serve as supports for the 30 roll of toilet paper.

Fig. 4 is a section taken on the line 4—4 of Fig. 3.

Referring by numerals to the accompanying drawing which illustrates a practical 35 embodiment of my invention, 10 designates a bracket that is preferably formed from a single piece of heavy wire or small metal rod and the end portions of the section of wire or rod from which the bracket is 40 formed are bent substantially at right angles to the intermediate portion so as to form a pair of horizontally disposed parallel arms 11.

The bracket may be secured to the wall 45 or other fixed support in any suitable man-

ner, preferably by means of a metal plate 12 having one edge bent so as to engage over the intermediate portion of the bracket and said plate being secured to the wall or other support by screws 13 or like fastening 50 devices.

The forward portions of the arms 11 are rebent so as to form relatively short fingers 14 that lie parallel and in the same horizontal plane with the forward portions of 55 the arms 11 and said fingers lying immediately adjacent to and outside said arms 11.

The rear ends of the fingers 14 or portions thereof, are bent inwardly at right angles and the ends of these bent portions bear 60 directly against the arms 11 and thus the forward portions of said arms and the parallel fingers 14 form horizontally disposed loops.

The hinged fingers 15 that serve to support the roll of toilet paper are preferably 65 formed of sheet metal and they are bent transversely to form curving upper faces that conform with the curvature of the heavy paper tube upon which the web of the 70 roll of toilet paper is wound.

The outer portion of each of these metal fingers is bent to form a loop 16 that encircles one of the fingers 14 and thus the supporting fingers 15 are mounted on the 75 forward portions of the arms of the bracket so as to swing upwardly from said arms.

The upward and outward swinging movement of each finger 15 is limited by an ear 80 17 that projects downwardly from the intermediate portion of the loop 16 and which ear is adapted to engage against the underside of the adjacent arm 11 when the finger 15 is swung upwardly and outwardly into an approximate vertical position.

Under normal conditions or when the fingers 15 are in position to support the roll of toilet paper, said fingers occupy horizontal planes, as illustrated by solid lines 85 90

in Figs. 2 and 4 and said fingers rest upon the outer portions of the arms 11.

To place a roll of toilet paper in the holder, the roll is positioned in a horizontal plane 5 just below and between the forward ends of the arms 11 and said roll is now moved upward between the forward portions of the arms and as the fingers 15 are engaged by the top of the roll they will swing upwardly 10 into the positions shown by dotted lines in Fig. 2 and as the upper portions of the ends of the tube on which the web of toilet paper is wound moves above the inner ends of the fingers 15, the latter will by gravity drop 15 downward into horizontal planes or until they rest on the forward portions of the arms 11 and the roll of paper is now lowered until the end portions of the tube on which the paper is wound, rest on the inward projecting fingers 15.

Thus the roll of paper is conveniently supported upon the fingers 15 and the web of paper may be unwound from the roll and torn off along the perforated or weakened 25 lines.

After all of the paper has been unwound from the tubular core the latter may be easily and quickly removed from the holder by moving said core upwardly so as to disengage the hinged fingers from the ends of 30 said core.

Thus it will be seen that I have provided a toilet paper holder that is relatively simple in construction, inexpensive of manufacture and very effective in performing the 35 functions for which it is intended.

The holder is constructed so that a roll 40 of toilet paper may be very easily and quickly positioned in the holder and the roll is retained and supported upon the holder so that the web of paper may be readily engaged and unrolled.

It will be understood that minor changes 45 in the size, form and construction of the various parts of my improved toilet paper holder may be made and substituted for those herein shown and described without departing from the spirit of my invention, the scope of which is set forth in the appended claims.

I claim as my invention:

1. A toilet paper holder, comprising a horizontally disposed bracket and a pair of roll engaging fingers hinged to the forward 55 portion of said bracket so as to swing upwardly and outwardly away from each other.

2. A toilet paper holder, comprising a bracket having a pair of horizontally disposed parallel arms and roll paper supporting fingers hinged to the forward portions of said arms so as to swing upwardly and outwardly away from each other.

3. A toilet paper holder, comprising a 65 bracket having a pair of horizontally dis-

posed parallel arms, roll paper supporting fingers hinged to the forward portions of said arms and cooperating means on said fingers and arms for limiting the vertical swinging movement of said fingers in both 70 directions.

4. A toilet paper holder, comprising a bracket having a pair of parallel arms, a pair of gravity fingers hinged to the forward portions of said arms and projecting toward each other and means carrying said gravity fingers for engaging the arms and limiting the upward swinging movement of 75 said fingers.

5. In a toilet paper holder, a bracket and a pair of roll toilet paper supporting fingers hinged to said bracket so as to swing in a vertical plane and said fingers projecting toward each other and occupying the same 80 horizontal plane.

6. In a toilet paper holder, a bracket and a pair of roll toilet paper supporting fingers hinged to said bracket so as to swing to a vertical plane, said fingers projecting toward each other and occupying the same 85 horizontal plane and cooperating means on said fingers and bracket for limiting the upward swinging movement of said fingers.

In testimony whereof I affix my signature.

JOSEPH H. ALLEN.
